UNITED STATES PATENT OFFICE

158,229

TWO-PIECE COAT ENSEMBLE

Sam Stein, Chicago, Ill.

Application September 16, 1948, Serial No. 148,614

Term of patent 3½ years

(Cl. D3—4)

To all whom it may concern:

Be it known that I, Sam Stein, a citizen of the United States, residing at 5 South Wabash Avenue, Chicago, Illinois, have invented a new, original, and ornamental Design for a Two Piece Coat Ensemble, of which the following is a specification, reference being had to the accompanying drawing, forming a part thereof.

I claim:

The ornamental design for a two-piece coat ensemble, substantially as shown.

SAM STEIN.
